UNITED STATES PATENT OFFICE.

ALBERT J. D. OHM, OF OAK PARK, ILLINOIS, ASSIGNOR TO R. WILLIAMSON & COMPANY, OF CHICAGO, ILLINOIS, A CORPORATION OF ILLINOIS.

DESIGN FOR A LIGHTING FIXTURE.

Application filed April 13, 1929. Serial No. 30,872. Term of patent 7 years.

To all whom it may concern:

Be it known that I, ALBERT J. D. OHM, a citizen of the United States, residing at Oak Park, in the county of Cook and State of Illinois, have invented a new, original, and ornamental Design for Lighting Fixtures, of which the following is a specification, reference being had to the accompanying drawing, forming a part thereof, in which—

Fig. 1 is a plan view of the canopy which constitutes a part of the fixture design of Fig. 2.

Fig. 2 is an elevation of the lighting fixture with shades shown in broken lines to indicate their location on the fixture; and

Fig. 3 is a bottom view of the fixture also showing the shades in broken lines for the same purpose.

I claim:

The ornamental design for a lighting fixture, as shown.

ALBERT J. D. OHM.
